UNITED STATES PATENT OFFICE

2,439,211

SUBMARINE MINE

Clarence N. Hickman, Washington, D. C., assignor
to the United States of America as represented
by the Secretary of the Navy

Application November 13, 1924, Serial No. 749,644

9 Claims. (Cl. 102—14)

1

This invention relates to improvements in submarine mines and more particularly in self-calibrating devices for what are generally known as drifting mines or pursuit mines, that is, a ship being pursued drops a number of mines in its wake which come to rest at a predetermined distance below the surface of the water and occupy that suspended position to be engaged by the pursuing vessels.

One of the objects of the present invention is to provide an improved mine of the above character which will be self-calibrating, that is, come automatically to a position of rest at a predetermined distance below the surface of the water.

A further object is to provide a mine of the above general character with a self-calibrating device which may be inexpensively manufactured and installed on standard equipment without material modification of existing parts.

Other objects will be in part obvious and in part hereinafter pointed out in connection with the accompanying sheet of drawing illustrating one of various possible embodiments of the present invention.

In this drawing,

Figure 1 is a sectional, elevational view of such parts of the calibrating device and mine casing as are necessary to understand the invention.

Figure 2 is a side elevational view of a portion of the device and,

Figure 3 is a detail view of one of the discs.

Referring now to Figure 1, 1 indicates the mine case which is of usual spherical construction adapted to contain a firing mechanism and an explosive charge, these parts being of such well-known construction and installation that a description or detailed statement is believed to be unnecessary.

Within this mine casing is a main support 2 for the internal mechanism of the calibrating device, this part being screwed up against the mine case as shown and provided with a rubber gasket 3 and lock nut 4. A bracket 5 on the exterior of the mine case is adapted to support the detachable weights, as will be hereinafter more fully explained. Within the mine case is a cylinder 6 adapted to be clamped against the member 2 by means of a collar 7. One end of a flexible rubber sleeve 9 is folded back upon itself around a brass ring 8 as shown and makes a water tight joint between the parts 2 and 6 and at the same time forms a means for securing one end of this sleeve 9. At the end of the cylinder is a cap 10 containing three guide rollers 11 for supporting a movable rod 23 extending through

2

the cylinder as shown. Surrounding this rod 23 is a member 12 acting as a support for one end of the spring 13 while at the opposite end is a similar support 14 for a similar spring 13'. This part 14 is adapted to screw onto a member 15 which takes up against the internal tube 16 and clamps the other end of the rubber sleeve 9 wrapped around its supporting ring 17. The part 15 also supports the rod 23 as well as an extension thereof or rod 24 which is supported by rollers 20 which act as guides for the rod 24 and its extension 25. A pin 18 protrudes from the part 2 and acts as a lock to prevent the member 15 from turning while tightening up the rod 25 by means of its threaded engagement with the rod 24. The two guides 21 secured to the bracket 5 are provided with spacers adapted to hold discs 26 in their proper position, the rod 25 keeping the discs from dropping off until the desired time.

20 In Figure 2 there is shown a plan view of the disc weights and,

Figure 3 is a detailed view of one of the disc weights. Piece 21 acts as a support for the springs 13 and carries guide rollers 22.

25 It will be noted from these drawings that the lower support 27 engages a notch 28 and as the pin 25 is withdrawn from the hole 30, Figure 3, then the disc is free to roll in the direction of the arrow, Figure 2, and drop from the lower support 27.

In operation when the mine is planted or released from the pursued ship, for example, it sinks until the external water pressure is sufficient to overcome the initial tension of the 30 springs 13. (This should be adjusted to approximately 50 feet.) When the mine reaches this depth the moving piston 15 begins to compress the springs 13, moving inward and pulling the rod 25 with it. As soon as it has moved about .3 inch the first weight is permitted to drop off. In like manner for each .3 inch motion of the piston it drops one of the disc weights. This continues until a sufficient number of discs have been dropped to properly calibrate the mine. 45 When the mine begins to rise the springs 13 push the piston out which in turn pushes the rod 25 back to its original position thus retaining the remaining disc weights. If, for any reason, the mine should become heavy due to leakage or 50 water absorbed by the floats, it will again sink until it has dropped off weights enough to again properly calibrate itself.

In other words the principle upon which this mechanism operates is as follows: The mine, together with the attached device is planted in

the usual manner. The negative buoyancy of the system is supposed to have been adjusted to approximately ten pounds. The mine sinks until it gets to a depth of approximately fifty feet at which point a two pound weight is released. If the mine is still heavy, it continues to sink and after travelling five feet deeper, another two pound weight is released. The mine keeps on sinking, dropping a two pound weight for about every five feet of travel until the unit no longer has negative buoyancy. After having dropped the weight which changes the negative buoyancy of the system to a positive buoyancy, the system slowly rises until the top buoy reaches the surface. If two pound weights are used as suggested, the positive buoyancy of the unit must always be less than two pounds and greater than zero. It will thus be seen that it is not necessary to have a top buoy with a positive buoyancy of more than about three pounds. A buoy of this type made of cork need be no more than five inches in diameter and about five inches long. It would be extremely difficult, if possible, to locate a buoy of this size under usual service conditions. In addition to this great advantage, that is, making it unnecessary to use a large buoy on the surface, a mine equipped with such a self-calibrating device will adapt itself to sea-water of most any density and temperature.

It is exceedingly difficult to load a large number of mines so that they will have exactly the same buoyancy. The use of such a self-calibrating device would make it unnecessary to load the mine with such a high degree of accuracy.

The self-calibrating device herein described contains ten two-pound weights. If, in loading the mines, an attempt is made to obtain a negative buoyancy of ten pounds, it will calibrate itself correctly even if there is an error of ten pounds in the adjustment, either light or heavy. This gives a total possible variation in the weights of the mines of twenty pounds. If it is so desired, a greater number of weights may be used. This will increase the possible errors in the calibration or the variations in buoyancy due to the salinity and temperature of the sea-water.

It will thus be seen that the present invention comprehends a simple and practical self-calibrating device for drifting mines which may be inexpensively manufactured, assembled and installed on standard mine equipment without material modifications or interfering in any way with the mine explosive charge or the firing mechanism therefor.

What I claim is:

1. In combination with a mine casing, a plurality of detachable weights pivotally supported on the exterior of the mine, a rod supporting said weights, and a piston within the casing subjected to hydrostatic pressure and actuating the rod whereby as said piston moves, on increase of hydrostatic pressure, the rod will be retracted to progressively release the weights until a substantial state of equilibrium is reached.

2. In combination with a mine casing, a plurality of detachable weights pivotally supported externally thereof, each of said weights being apertured, a rod passing through the apertures, a hydrostatic piston within the mine connected

with and actuating said rod and adapted to be moved on increase of hydrostatic pressure, and spring means reacting upon said piston for restoring the rod to normal position should the mine come to the surface.

5 3. In combination with a mine casing, a plurality of detachable weights externally mounted thereon, a retractable rod extending through the casing and engaging with the weights, and a piston subjected to hydro-pressure connected with the rod for progressively disengaging the latter from the weights upon increased hydrostatic pressure on the former.

10 4. In combination with a mine casing, a plurality of detachable weights externally mounted thereon, each of said weights being apertured, a cylinder within the casing, a piston subjected to hydrostatic pressure operable within the cylinder, a rod connected to and movable with the piston, said rod passing through the apertures and progressively disengaging them when the piston is moved by increased hydrostatic pressure thereupon, and means for restoring the piston and rod to normal position when the pressure is decreased.

25 5. In a submarine drifting mine, in combination, a casing, a reducible weight composed of a plurality of individual units each pivotally supported exteriorly of the casing, and hydrostatically controlled means for progressively releasing said units in accordance with the depth of the mine.

30 6. In a submarine mine, a casing, a plurality of weights detachably supported exteriorly of the casing, a retractable rod carrying each of the weights, and a hydrostatic means for retracting the rod to release the weights progressively.

35 7. In a submarine mine, a casing, a plurality of weights detachably supported on the exterior of the casing, a retractable rod carrying each of the weights, and a hydrostatic means for retracting the rod to release the weights.

40 8. In a submarine mine, a casing, a rod retractable through the casing, a plurality of weights each carried by and supported on the rod exteriorly of the mine casing, and hydrostatic means to retract the rod for progressively reducing the number of weights.

45 9. In a submarine mine, a casing, a plurality of weights, each weight eccentrically supported on the exterior of the casing about the same axis, and hydrostatic means for progressively reducing the number of weights.

CLARENCE N. HICKMAN.
